DRIVE FOR A ROLL TO MAINTAIN
CONSTANT WEB STRESS

Karl Gustav Tiselius, Västerås, Sweden, and Nils J. E. Haglöf, Wanstead, London, England, assignors to Allmanna Svenska Elektriska Aktiebolaget, Västerås, Sweden, a corporation of Sweden

Application May 27, 1939, Serial No. 276,137
In Sweden April 25, 1938

3 Claims. (Cl. 242—75)

The present invention refers especially to the drive of printing presses and has for its object an arrangement for the maintaining of a constant stress in the paper running through the printing press, but the invention is not limited to the drive of printing presses but can also be applied in other cases where it is necessary to run a ribbon- or wire-formed material with a constant stress through a machine.

In printing presses a suitable stress in the paper running through the press generally is achieved thereby that the roll from which the paper is unwound, is braked in one or other manner. In many cases this is achieved by the aid of an electric machine acting as generator. In order to avoid jerks in the paper due to the speed variations of the press the electric machine, which is coupled to the roll from which the paper is unwound must be so regulated that the peripheral speed of the roll becomes the same as the speed of the web in the press. The braking machine has previously been regulated by means of a member which has measured the tension in the paper. This member has previously generally been a lever with a roll at the end which has pressed against the web and caused a deflection in the web. The motions up and down of the roll due to the variations in the stress of the paper have been transmitted by the lever to the member which has regulated the braking machine. It has, however, been shown by the practice that due to the large speed of the paper in modern printing presses and due to the large masses in modern printing presses such a regulation is not sufficient because it acts too slowly. When the speed of the press suddenly changes the member measuring the stress in the paper has not time enough to regulate the braking electric machine so that the stress in the paper will often be so large that the paper is torn or becomes slack if the press is suddenly braked.

The present invention has for its object an arrangement for regulating the braking electric machine which is distinguished by a considerably larger rapidity than other known arrangements. According to the invention the braking electric machine is regulated not only in dependence of the stress of the paper but also in dependence of the difference between the speed of the web and the speed of the paper unwound from the roll.

On the accompanying drawings Fig. 1 shows schematically an arrangement according to the invention. Fig. 2 is a diagram which shows the regulating operation in hitherto known arrangements and Fig. 3 is a diagram which shows the

regulating operation of the arrangement shown in Fig. 1.

In Fig. 1, 1 designates the paper which is unwound from the roll 2. This paper runs over two rolls 3 and 4 and over the roll 5 which is pulled down by a helical spring 6 and is pivoted in a lever 7 movable around the point 8. At the other end of the lever 7 is one end of a wire 9 fastened and this wire is wound around a roll 10 on the shaft of the regulating resistance 12. The other end of the wire 9 is fastened to a helical spring 11 which acts in a direction opposite to that of the spring 6 so that the wire 9 is always stretched. The rolls 3 and 4 are each coupled with the tachometer generators 13 and 14 which are excited from a constant direct current source.

The roll 2 is attached to a shaft 15 to which is coupled a three-phase commutator motor with speed regulation by brush displacement. This motor is on the drawing designated by 16, and 17 is a tooth rim which is connected with the bridge carrying the brushes. With this tooth rim engages a pinion 18 which is attached to a shaft connected with the brush displacement motor 19 which shaft also is connected with the counter regulation generator 20.

The two tachometer generators 13 and 14 are coupled in series but so that they counteract each other and are in series with a part of the resistance 12 connected to the coil 21 of the rapid regulator 22. This consists of a balance 23 which is pivoted on an edge 24 and is held in balance by two helical springs 25. The balance carries an arm 26 which carries two contacts 27 and 28 coating with the stationary contacts 29 and 30. The coil 21 as well as the counter regulation coil 31 move in the air gaps of the permanent magnets 32 and 33 respectively. The contact pairs 29 and 30 are in cross connection connected to a source of constant voltage and the contacts 27 and 28 are connected with the terminals of the brush displacement motor 19.

The counter regulation coil 31 is in series with the counter regulating generator 20 connected with a regulable inductance coil 34 and the contact arm 35 of this coil is connected with a roll 36 which rests against the surface of the paper roll 2.

The action of the arrangement is the following: As long as the stress in the paper 1 is constant the balance 23 of the rapid regulator 22 swings around its zero position and the brush displacement motor 19 receives over the contacts 27 and 28 equal long current impulses for the motion in both directions so that the mean position of

the brush bridge 17 is maintained and the motor 16 runs with constant speed and constant torque. If due to any cause the speed of the printing press should be altered the roll 5 moves upwards or downwards with a certain speed and this motion is a direct measure of the change of the stress in the paper. Due to its inertia the roll 2 at the beginning of the regulation can not change its speed and the speed of the roll 3 will therefore 10 at the beginning remain constant whereas the speed of the roll 4 already from the beginning of the regulation will change its speed in accordance with the speed of the paper press. There will thus be a voltage difference between the two tachometer generators 13 and 14 and this voltage difference is added to the voltage drop over the resistance 12. The coil 21 on the regulator 22 will therefore be traversed by a current which on one hand is dependent on the position of the roll 5 and on the other hand on the difference in speed between the rolls 3 and 4. Due to the change in the current through the coil 21 the balance 23 of the regulator 22 will swing around another mean value 20 so that the brush displacement motor receives impulses for driving the brush bridge connected with the tooth rim 17 in the one or the other direction and the speed of the machine 16 is then changed so that the speed of the paper unwound 25 from the roll 2 becomes the same as the speed of the paper running through the press. When the speed of the printing press is constant the machine 16 is so regulated that the stress in the paper remains constant.

In order to avoid an over-regulation the brush displacement motor 19 in previously known manner is connected with a small generator 20 which gives a current through the coil 31 in the rapid regulator 22 which current is proportional to the speed of the brush displacement. In order that the regulation may be entirely free from hunting the recalling achieved by means of the coil 31, however, must be in a certain relation to the inertia of the system to be regulated, i. e. the 40 inertia of the motor 16 and the roll 2.

If the roll 2 decreases in size the current through the regulating coil 31 thus must decrease in the same manner and this variation is achieved by means of the inductance 34, which due to the 45 fact that its contact arm 35 with one end rests against the surface of the roll 2 to a large or smaller extent is inserted in the circuit of the coil 31.

In the diagram Fig. 2 the operation of the hitherto known arrangements is shown, i. e. when the braking machine only is regulated with respect to the stress in the paper. It is assumed that the press is stopped on the point P₁. Due to its inertia it can not stop immediately, but only after 10 to 15 seconds which time on the diagram is represented by the distance between the points P₁ and P₂. During this time the speed of the press decreases practically along the straight line V₁, which also represents the speed of the paper in the press. As the speed of the paper coming from the roll 2 still is constant the roll 5 will move downwards and the motion of the roll 5 is in the diagram represented by the line S. As the regulator, however, needs a certain minimum impulse in order to give a distinct and rapid regulation the roll 5 must move a certain way before the regulations of the machine 16 can commence and this takes place at first at the point P₃ and then the speed V₂ of the paper unwound from the roll is changed along a line

shown by the line V₂ on the diagram. First when the line V₂ intersects the line V₁, at point P₄, the roll 2 has been retarded so much that its peripheral speed is equal to the speed of the paper in the press. As, however, the speed of the paper unwound from the roll during the time before has been larger than the speed of the paper in the press plenty of paper has been assembled in front of the press. It is thus obvious that if the press without any disadvantages shall be able to be stopped in the above mentioned short time which with respect to the service may be necessary, it is necessary that the regulation is such that no assembling of paper in front of the press takes place. According to the invention 15 such a regulation is achieved thereby that the braking machine is regulated not only with respect to the stress in the paper but also with respect to the difference between the speed of the paper in the press and the surface speed of 20 the paper of the roll. The operation of such a regulation is illustrated in Fig. 3. In the diagram Fig. 3 the points P_{1x} and P_{2x} correspond to the points P₁ and P₂ of Fig. 2 while the lines V_{1x} and V_{2x} correspond to the lines V₁ and V₂ of 25 Fig. 2, and S₁ designates the motion of the roll 5. As the regulator of the machine 16 in this arrangement is actuated by a quantity which is proportional to the sum of the motion of the roll 5 and the speed difference between the two 30 paper webs, i. e. the web in the press and the web unwound from the roll 2, the regulation will commence at a much earlier stage at the point designated by P₅. As seen from the diagram equality in speed between the two paper 35 speeds is reached at a much earlier stage due to the fact that the regulating of machine 16 commences much earlier. Equality in speed is reached at the point P₆. The amount of paper assembled in the front of the press will thus be 40 much smaller and by an overregulation the paper assembled in front of the press during the first part of the braking period may be taken up during the latter part of it, so that before the press stops the stress in the paper has reached its 45 normal value. In reality a so rapid regulation can be reached by the present invention that no paper at all is assembled in front of the press, the roll 5 moving downwards only a little and the stress in the paper will be practically constant all 50 the time.

We claim as our invention:

1. In a rotary printing press or other machine, a web of a ribbon- or wire-formed material running through the machine, a reel from which the web is unwound, an electric generator coupled to the reel and braking the reel, two stationary lead rollers, a movable lead roller arranged between said stationary rollers, a regulator controlling said braking generator, means for actuating said regulator in accordance with the difference in speed of said stationary rollers, means for actuating said regulator in dependence of the stress in the web measured by the position of said movable roller. 65

2. In a rotary printing press or other machine, a web of a ribbon- or wire-formed material running through the machine, a reel from which the web is unwound, an electric generator coupled to the reel for braking it, two stationary lead rollers, two tachometer generators coupled to said rollers, a movable lead roller arranged between said stationary rollers, a spring actuating said movable lead roller, a resistance varied by said movable lead roller, a regulator controlling said 70 75

braking generator, said regulator being actuated by the voltage difference between said tachometer generators and the voltage drop over the resistance actuated by the movable roller.

- 5 3. In a rotary printing press or similar machine, a web of a ribbon- or wire-formed material, a reel from which the web is unwound, an electric generator coupled to the reel for braking it, two stationary lead rollers, two tachometer
10 generators coupled to said lead rollers, a movable lead roller arranged between said stationary rollers, a resistance varied by said movable lead roller, a regulator controlling a speed regulation device on said braking generator, a counter reg-

ulation generator coupled to said speed regulating device, a regulable resistance inserted in series of the counter regulation generator, said resistance being varied by a lever resting with one end on the surface of the reel, the said regulator being actuated by the voltage difference of the two tachometer generators, the voltage drop over the resistance coupled to the movable roller, the voltage of the counter regulation generator, and the voltage drop over the resistance varied by 10 the lever resting on the surface of the reel. 5
